UNITED STATES PATENT OFFICE.

CLARENCE R. GILLETT, OF CHICAGO, ILLINOIS, ASSIGNOR TO HENRY W. LEMAN, OF SAME PLACE.

METHOD OF AND APPARATUS FOR GENERATING ACETYLENE GAS.

SPECIFICATION forming part of Letters Patent No. 611,473, dated September 27, 1898.

Application filed August 26, 1898. Serial No. 689,543. (No model.)

To all whom it may concern:

Be it known that I, CLARENCE R. GILLETT, a resident of Chicago, Cook county, Illinois, have invented certain new and useful Improvements in Methods of and Apparatus for Generating Acetylene Gas, of which the following is hereby declared to be a full, clear, and exact description.

The invention designs to sensitively control the supply of water flowing from a confined storage-tank into the carbid-retort by compelling the feed to proceed under definite tension—*i. e.*, pressure at the tank—according to the demand in the consumption-circuit, as this is reflected by the resultant pressure existing at the retort. When the retort-pressure falls below an assigned normal or what may be termed the “definite maximum,” water begins to flow from the tank and thereupon persists until the selected normal at the retort is exceeded. Further water-supply then becomes checked or suspended and is not resumed until the retort-pressure again drops below the normal. The tension over the tank-supply is kept practically constant irrespective of changes in the water volume at the tank and also irrespective of any excess pressure condition which may exist at the retort. If a given water volume in a confined tank be diminished so that the gas-space above it is doubled, it is plain that the tension exerted becomes only one-half. Into such rarefied medium the surplus gas, which constitutes the retort-pressure, would generally force its way. The tendency always is to establish an equilibrium between the pressure at the retort and the tension at the tank. The invention prevents this and yet assures uniformity of water inflow, dependent merely upon consumption needs and essentially independent of the gradually lessening volume of water present in the storage-tank. Unless the tension at the tank be kept practically constant the evolution of gas at the retort becomes irregular—*i. e.*, either suddenly excessive should the tank-tension markedly increase or else feebly insufficient should such tension gradually wane. These irregularities are wholly avoided. According to the invention the gas evolved at the carbide-retort may go directly into the main pipe-line or distribution-circuit without passing through

an intermediate gasometer or like storage-reservoir. By this provision space and outlay are economized, repairs and disorders are lessened, while the product is higher in quality than if subjected to gasometer exposure.

In automatic apparatus of the water-supply sort when consumption ceases at the burners the aim is to stop the inflow of water at the carbide-retort and thus to arrest the further generation of gas; but the action is not exact. There is apt to be a residual evolution of gas, due to the presence of surplus water in the retort. The confined pressure accumulates and would become excessive unless relieved by safety-vent or by providing a gasometer. Relief by safety-vent means waste. Objections to the gasometer have already been stated. The invention designs to hold the water inflow at the retort in closer and more sensitive control. Residual evolution is minimized, the subsidiary volume of gas being retained by the retort without undue pressure and without reflecting an excess tension upon the main supply of water at the feed-tank.

The exact nature of the improvements will appear in detail from the description following and be pointed out by claims at the conclusion.

On the drawing which accompanies one form of apparatus suitable for practice of the invention is shown in longitudinal section, with some of the parts displayed in elevation.

The retort A for the carbide is conveniently cast in box-like form with an open or exposed front after the fashion of a burglar-proof safe. A door to close against the jamb of the retort front is carried by upper and lower curved arms hinged thereto near its central vertical line. Said arms are also hinged at opposite ends in lugs projecting from the side of the retort at the front corners. By such expedient the door can close flat against a gasket at the jamb and be secured gas-tight by suitable eyebolts or like fastener extended at intervals between companion lugs on the edge of the door and the body of the retort. When the door is open, all parts of the retort interior are freely accessible.

At about its mid-height the retort carries the horizontal internal ledges 41 to sustain the carbide-tray 40, having wire-cloth or like

open bottom. A deep pan 49 rests upon the floor of the retort to serve as a receptacle for spent lime and possible surplus water. When the door is open, the pan can be easily emp-
5 tied and replaced and the tray be refilled with its charge.

A short shaft 44, extended through stuff-
ing-box 45 and its cap 46, carries internally
10 a cam-disk 43 and is furnished at its outer
end with crank-arm 47. By turning the
crank-arm the disk 43 impinges against the
face of tray-frame 40 to shake the tray up
15 and down and thus to dislodge the spent-lime
powder. A clip 48, suspended beneath tray
15 40, may receive a lump of carbid sufficient to
put the apparatus under desired pressure at
the outset. On turning crank-arm 47 the
piece of carbid is dislodged from clip 48 by
20 the shaking of tray 40 and drops into a minor
film of water at the pan 49 beneath. There-
upon acetylene gas is developed and forces
its way from the retort into the water-tank
25 and the distribution-circuit, as presently de-
tailed.

25 Water-tank 63 is mounted conveniently
above the retort by pipe 62, which is threaded
to a reducer-coupling 70, said coupling screwing
30 in turn into an opening at the tank bot-
tom. The casing of a stop-valve 71, here
30 shown as an ordinary one-way check-valve,
is joined to the protruding end of pipe 62
and may be coupled to a turn-cock 72, united
below to the outer terminal of a percolator 56.
Hand turn-cock 72 can be dispensed with.

35 Percolator 56 is threaded to and projects
within the carbid-retort and preferably con-
tains a wad 57 of wick or like obstructive
septum serving as a water-distributer. Cowl
58 screws onto the lower end of a percolator 56
40 and carries a pendent curtain 59, slit, as
shown, and which may be made from some
suitable capillary fabric. Disk 60, perforated
at the mouth of the percolator, clamps the
curtain 59 to cowl 58. The disk and cowl
45 are properly riveted together and the rivets
soldered over to prevent the water from seep-
ing past them. From tank 63 the water
emerges through vent 64 into pipe 62 and
thence past valve 71 and cock 72 into perco-
50 lator 56, saturating wad 57 and eventually
the curtain 59. With equal pressures exist-
ing at the tank and in the retort there will
generally be no drip of water onto the carbid.
Wad 57 suffices to obstruct the inflow. More-
55 over, check-valve 71 by aid of its spring will
ordinarily remain tightly closed upon its seat
under mere condition of like pressures at
both tank and retort, acting thus to sustain
the tank-water against any chance drip or
60 casual infeed.

To provide for the water flow, it is neces-
sary that the tension at the tank shall be-
come superior to the pressure existing in the
retort, and, besides, generally sufficient to
65 overcome the resistance of check-valve 71.
Ordinarily an even tension of, e. g., five
pounds exerted over the free surface of water

in the close tank will act to promptly open
the valve 71 and yet allow for speedy return
of the valve to its seat against such tension
70 when the retort-pressure due to generated
gas reaches, e. g., five pounds or more. Al-
though valve 71, with its spring, may be nicely
balanced to resist inflow at equal pressures,
as under ordinary atmospheric conditions, it
75 is seen that a slight drop in pressure at the re-
tort, due, e. g., to withdrawal of gas in the con-
sumption-circuit, speedily establishes a sub-
normal in the retort sufficient to induce a flow
80 of water from the tank. The degree of ten-
sion existing at the tank will determine the
rapidity of infeed.

Various expedients may serve to supply and
sustain the desired pressure over the confined
water-supply at the tank. Thus, as displayed
85 by the drawing, an educt, which, as here
shown, may conveniently be the exit-pipe 50,
constituting in effect an extension of the re-
tort proper, leads the gas from the retort and
by conduit 73 unites overhead with the top
90 of tank 63. A reduction-valve 74, of any ap-
proved pattern, such as shown, and a check-
valve 75, opening toward the tank, are inter-
posed in conduit 73. By adjusting its plun-
ger valve 74 can be set to close at, e. g., five
95 pounds. Admission of gas to tank 63 in ex-
cess of such selected limit is thereupon pre-
vented, insuring an even tension of, e. g.,
five pounds over the free surface of the liquid.
The reduction-valve opens automatically to
100 admit an additional supply of gas to the tank
whenever the tension there drops below the
chosen limit. Instead of discharging directly
over the water the gas can deliver into an
expansion-bag contained in the water-tank.
105 Check-valve 75 prevents any back leak of
gas from the tank. This is a necessary pre-
caution if the gas be derived from the retort
or from the main line, since it is plain that
the gas at the tank would otherwise drain
110 away on any sudden draft coming from the
consumption-circuit. The pressure-reducer
and check-valve mechanism are thus shown
to coact not only in admitting an isolated vol-
ume of gas to the tank distinct from the main
115 supply, which never passes through the tank,
but also serves to confine such minor volume
against any material escape of loss in tension.
Under pressure of the confined gas it is plain
that the feed will occur, although the water-
120 tank were set at the level or below the carbid-
retort. By mounting the tank above, as here
shown, merely less pressure is requisite to
compel an infeed.

Conduit 73 to the tank 63 may lead from re-
tort A by an educt separate from that which
pertains to exit-pipe 50, appropriate to the
main line. Indeed, the requisite tank-tension
need not be derived from the retort but
be established instead, as by use at intervals
125 of a simple hand-pump connected with con-
duit 73, or, again, by uniting conduit 73 with
the train-pipe of a car brake system or like
source of supply which may automatically

establish the requisite tension at the tank under admission control of the pressure-regulator 74. If the source of supply has always a tension superior to that needed in tank 63, it is clear that check-valve 75 becomes superfluous in the absence of any "back draft" away from the tank. However derived, it is obvious that the volume of gas confined at the tank exerts its tension to feed the water into the retort whenever the pressure at the retort falls lower than the assigned normal by reason of the exit of gas from the retort into the main line for consumption.

As already explained, check-valve 71 can be nicely balanced to allow for the flow of water from tank 63, but so as to close snugly against its seat if the gas at the retort exerts an opposite pressure—*e. g.*, five pounds or more—upon the valve. By such provision water-tank 63 is relieved from excessive strain, while the tension of the gas confined therein never mounts to impel an undue feed of water. The precaution is important, especially if conditions be extreme—as, for instance, when a sudden draft comes upon the retort for a maximum volume of gas to supply a multitude of burners simultaneously lighted. Under copious evolution the gas must tend to force its way through pipe 62 into the tank, but stop-valve 71 checks this tendency and holds the tank-tension at the definite uniform limit assigned thereto, such limit ranging as appears, *e. g.*, from three to six pounds pressure, none of which pressure would exist were the tank open to the air.

The main supply of gas finds convenient exit from the retort, as at pipe 50. Trap 54, having petcock 55, enables the condensable products to be tapped off at intervals. Globe-valve 51 closes the distribution-circuit when, for example, the retort needs to be opened for replenishing. As here shown, the line-pipe from the retort carries a reducing-valve 76 similar in structure to valve 74, but adjusted to close at a nominal pressure—*e. g.*, one-half pound, more or less—on the delivery side.

The presence of the reducing-valve 76 enables the main line to deliver gas at the various burners under practically uniform tension. A gasometer may be employed instead or in conjunction therewith; but its presence is superfluous and ordinarily undesirable. The pressure at the consumption side is generally much lower than at the retort side of the reducing-valve; but as the gas passes off at the burners the lessening tension finally allows valve 76 to open and to admit a further volume of gas from the retort to the distribution-circuit. Thus at times the gas may be stored at the retort under pressure, *e. g.*, of twenty pounds, especially if the apparatus has remained inactive or has been subjected to sudden draft upon its store and consequent rapid inflow of water. Whatever the cause, reducing-valve 76 controls the escape, and,

despite the comparatively heavy pressure at the retort, none the less governs the tension on the distribution-circuit and holds the gas at low pressure merely sufficient to provide proper feed at the burners.

Generally it is not desirable to maintain a pressure in the main-line circuit much exceeding one-half to one pound; but if the joints are tight and the burners easily adjustable the pressure can be higher. In such event the conduit 73 may lead directly from the line-pipe to the tank, the reducing-valve 74 being dispensed with as superfluous, while the single reducing-valve 76 is made to act in dual capacity, controlling the pressure on the line and in the water-tank as well. The presence of check-valve 75 in conduit 73 would still serve to prevent undue escape of the confined volume from the water-tank if some sudden exhaust-draft comes upon the main line.

Should water-feed valve 71, interposed in pipe 62 between tank 63 and percolator 56, fail temporarily to act for any cause, the result will be to quickly establish an equal pressure of gas at the tank and in the carbid-retort beneath. Under such condition wad 57 restrains the flow of water. No additional volume will discharge into the retort unless and until the pressure there falls below the tension in the tank. This reduction in pressure ensues when the consumption-circuit is open, which means that the generation of gas will thereupon proceed automatically according to the demand and despite the dis-order of valve 71. Eventually the tension at the tank must gradually increase. Owing to this objection and the consequent risk, it is plain that due care must be taken to keep valve 71 in working order.

In lieu of the simple check-valve actuated directly by gas-pressure from the retort a turn-cock can be inserted across the water-feed tube and be controlled, as well understood, by means of a spring-piston, which is made to shift under varying conditions of retort-pressures.

A safety-vent at the water-tank may be employed to relieve any excess pressure, such as might accumulate there were valve 71 inactive. Save for the exceptional condition noted the safety-vent would stay unopened. Tube 65, closed gas-tight by cap 66, is inserted in tank 63 and admits the water-supply. Tube 65 overflows and denotes when the tank is sufficiently full.

Obviously the details of structure can be varied according to the mechanic's skill without departing from the essentials of the improvement.

Having thus described my invention, what I claim as new, and desire to secure by Letters Patent, is—

1. The method of generating acetylene from metallic carbids which consists in establishing a definite, uniform gas-pressure upon the confined water-supply, and when such pres-

- sure exceeds that present at the carbid charge, injecting the water thence under the resultant superpressure onto said charge, intermittently checking the inflow under extra normal pressure of the evolved gas and, as evolution proceeds, automatically maintaining such definite pressure on the confined water-supply to keep the same essentially even despite the variations in pressure of the evolved gas, substantially as described.
2. The combination with the carbid-retort and with the line-pipe leading therefrom to the distribution-circuit, of the close water-supply tank, the feed-tube intermediate said tank and retort and having a stop-valve to check the flow of water from tank to retort through said tube, by such pressure when the same exceeds that present in the retort, and for automatically maintaining the definite gas-pressure at said tank despite the variations in pressure at the retort, substantially as described.
3. The combination with the carbid-retort and with the line-pipe leading therefrom to the distribution-circuit, of the close water-supply tank, the feed-tube intermediate said tank and retort, the stop-valve to check the flow of water from tank to retort through said

tube, a pressure-pipe leading into said tank and the reducer and check-valve mechanism to allow delivery of gas at definite tension by said pipe into said tank and to there detain it under practically uniform pressure, substantially as described.

4. The combination with the water-supply tank and with the carbid-retort, of the intermediate feed-tube, the stop-valve to check the flow of water from tank to retort through said tube, the pressure-pipe in communication between retort and tank, and the reducer and check-valve mechanism to deliver gas at definite tension by said pipe from retort to tank and there detain it under practically uniform pressure, substantially as described.

5. The combination with the carbid-retort and with the water-supply tank, of the intermediate feed-tube having one-way check-valve therein, the line-pipe leading from the retort to the distribution-circuit and furnished with a reduction-valve, and the pressure-conduit interposed between the retort and tank, discharging into said tank and having a reduction-valve and separate check-valve therein, substantially as described.
